DESIGN FOR AN ELECTRIC CONTROLLING DEVICE

Clifford Brooks Stevens, Milwaukee, Wis., assignor to Cutler-Hammer, Inc., Milwaukee, Wis., a corporation of Delaware

Application October 22, 1937, Serial No. 72,369

Term of patent 14 years

To all whom it may concern:

Be it known that I, Clifford Brooks Stevens, a citizen of the United States and a resident of Milwaukee, in the county of Milwaukee and State of Wisconsin, have invented a new, original, and ornamental Design for an Electric Controlling Device, of which the following is a specification, reference being had to the accompanying drawing, forming part thereof.

Figure 1 is a top plan view of an electric controlling device incorporating my new design.

Fig. 2 is a front elevational view thereof.

Fig. 3 is a side elevational view of the electric controlling device.

I claim:

The ornamental design for an electric controlling device, substantially as shown.

CLIFFORD BROOKS STEVENS.
